Attorney

UNITED STATES PATENT OFFICE.

ALFRED W. LAWSON, OF GREEN BAY, WISCONSIN.

PEDAL.

1,284,115.

Specification of Letters Patent.

Patented Nov. 5, 1918.

Application filed January 5, 1918. Serial No. 210,579.

To all whom it may concern:

Be it known that I, ALFRED W. LAWSON, a citizen of the United States, residing at Green Bay, in the county of Brown and

5 State of Wisconsin, have invented certain new and useful Improvements in Pedals, of which the following is a specification, reference being had to the accompanying drawings.

10 This invention relates to certain improvements in pedals and has relation more particularly to a device of this general character especially designed and adapted for use in connection with a rudder bar of an aeroplane, and it is an object of the invention to provide a device of this character provided with novel and improved means whereby the same may be caused to move with a minimum of frictional resistance.

20 Furthermore it is an object of the invention to provide a novel and improved pedal connected at its toe portion with a rudder bar or the like and provided at its heel portion with an anti-friction member adapted 25 to engage and travel over a surface adjacent the rudder bar whereby an effective support is afforded for a foot.

The invention consists in the details of construction and in the combination and arrangement of the several parts of my improved pedal whereby certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective of a pedal constructed in accordance with an embodiment of my invention, the coacting end 45 portion of the rudder bar being indicated by dotted lines; and

Fig. 2 is a view in cross section taken through the heel portion of my improved pedal as herein embodied.

50 As disclosed in the accompanying drawings P denotes a pedal of a slipper formation and which is adapted to snugly receive the foot of an aviator or the like. The toe portion of the pedal is engaged as indicated 55 at 1 with an end portion of a rudder bar R

of a type employed in connection with aeroplanes. Depending from the heel portion of the pedal is the tubular body or sleeve 2 cylindrical in form and provided at its upper end with the flange 3 to afford means whereby the body or sleeve 2 may be conveniently and effectively secured to the heel portion of the pedal. Loosely mounted within the lower or free end portion of the body or sleeve 2 is an anti-friction member 5 herein disclosed as a relatively large spherical member or ball and which is maintained within the body or sleeve 2 by crimping or inturning the lower marginal portion of the body or sleeve 2 so as to overlie the anti-friction member or ball 5 below the center thereof.

The anti-friction member or ball 5 rides upon a plate or other surface included in an aeroplane structure and positioned adjacent the rudder bar R. It will be perceived that as an operator forces an end portion of the rudder bar to effect a steering operation the heel portion of the pedal P will ride over such plate or other surface with a minimum of frictional resistance and at the same time permitting a universal movement of the heel portion of the pedal. At the same time it will be understood that by having the anti-friction member or ball 5 carried by the 85 pedal and in contact with the surface S, a support is afforded for the foot and which is of a decided advantage in use especially as relates to increasing the comfort of the operator.

90 From the foregoing description, it is thought to be obvious that a pedal constructed in accordance with my invention is particularly well adapted for use by reason of the convenience and facility with which it 95 may be assembled and operated and it will also be obvious that my invention is susceptible of some change and modification without departing from the principles and spirit thereof and for this reason I do not wish to 100 be understood as limiting myself to the precise arrangement and formation of the several parts herein shown in carrying out my invention in practice except as hereinafter claimed.

105 I claim:

1. In combination with an operating member traveling in a plane above a surface, a pedal operatively connected to said movable member, and an anti-friction member car- 110

ried by the pedal and riding upon the surface and permitting a universal movement of the heel portion of the pedal.

2. In combination with an operating member traveling in a plane above a surface, a pedal operatively connected at its toe portion to the member, and an anti-friction member carried by the heel portion of the pedal and riding upon the surface and permitting a universal movement of the heel portion of the pedal.

3. In combination with an operating member traveling in a plane above a surface, a pedal operatively connected at its toe portion to the member, a sleeve depending from the heel portion of the pedal, and a ball loosely mounted in the lower end of the sleeve and riding upon the surface and permitting a universal movement of the heel portion of the pedal.

4. In combination with an operating member, a pedal operatively connected at its toe portion to the operating member, and an anti-friction member carried by the heel por-

tion of the pedal to afford a support for the heel portion of the pedal and permitting said heel portion to have universal movement.

5. As a new article of manufacture, a pedal provided at its toe portion with means for operatively connecting the same to an operating member, and an antifriction member carried by the heel portion of the pedal and serving as a support therefor.

6. As a new article of manufacture, a pedal provided at its toe portion with means for operatively connecting the same to an operating member, and an anti-friction member carried by the heel portion of the pedal and serving as a support therefor, said antifriction member also permitting universal movement of the heel portion of the pedal.

In testimony whereof I hereunto affix my signature in the presence of two witnesses.

ALFRED W. LAWSON.

Witnesses:

W. E. LAWTON,
G. E. LEWIS.
